[57] CLAIM

The ornamental design for the caliper, as shown.

DESCRIPTION

FIG. 1 is a front and top-left perspective view of a caliper showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a cross-sectional view thereof as taken from line A—A of FIG. 4, the head end housing being omitted for ease of illustration.

FIG. 1

FIG. 2

FIG. 3

FIG. 6

FIG. 7

FIG. 8
